PIERRE DIEBOLD, OF NANCY, FRANCE

WASHING MACHINE

Application filed September 10, 1927, Serial No. 218,726, and in France February 5, 1927.

This invention relates to washing machines and its object is to remedy some drawbacks of the usual machines of the so-called splashing or ebullition type.

5 In machines of this kind, where the rotary drum dips into the washing liquid contained in an outer stationary jacket, the linen bubbles up and down in the washing liquid, so that the friction of the linen upon itself and against 10 the walls of the machine is deadened; the grease and other impurities removed from the linen accumulates on the inner surface of the washing drum and cannot be cleaned off during the operation, thus a good washing of the 15 linen cannot be obtained.

The door for introducing the linen into the previously known machines is placed on the cylindrical portion of the washing drum and causes a lack of balance; such machines are 20 generally driven by a mechanism including gears or noisy rack and pinion drives, and finally said machines require a separate apparatus for heating the washing liquid which increases the floor space of the machines and 25 which are not economical in fuel consumption.

One object of the present invention is to obtain a better washing of the linen and to this end the washing drum which is made of 30 perforated sheet metal as usual, is arranged so as not to dip into the liquid contained in the outer casing or jacket, and it is provided at its periphery with a set of buckets having an extension running radially towards the 35 center of the drum, which buckets, during the rotation of the drum, take water from the jacket and pour it over the linen through the perforations of the drum, so that the linen is treated by aspersion or sprinkling and not by 40 ebullition or effervescent-like seething.

In order to continuously clean off the inner surface of the drum from the grease and other impurities removed from the linen, another set of buckets, having no radial ex- 45 tensions is provided, taking water from the jacket and pouring said water over the lower portion of the inner surface of the drum.

Another object of the invention is to make the charging and discharging of the machine 50 more simple and easier and for this purpose

the usual door of the washing drum is done away with and the washing drum as well as the outer stationary jacket are open at one end so that the linen can be charged from said open end.

Another object of the invention is to do away with the usual separate heating apparatus and to this end the frame of the machine supporting the stationary jacket is shaped so as to form the heating casing. Said 55 casing is U-shaped and double walled surrounding a hearth or gas chamber containing a heat source. Thus the casing performs a double function of heating casing and support.

In the accompanying drawing:

Figure 1 is a cross section of the machine corresponding to the line 1—1 of Figure 2;

Figure 2 is a vertical section through the longitudinal axis;

Figure 3 is a horizontal section corresponding to the line 111—111 of Figure 1;

Figure 4 is a diagram of the controls;

Figure 5 is a vertical section of the automatic reversing mechanism for reversing the 75 rotations of the washing drum;

Figures 6 and 7 are two details of Figure 5.

The machine illustrated comprises a stationary jacket 1, preferably cylindrical, forming a water tank one of the faces of which 80 has a central opening 2. Circular angle pieces 1' join said jacket 1 and the faces thereof. This jacket is arranged upon a double-walled casing 3 of horse-shoe shape (Figure 3) the space between the walls being filled 85 with water and constituting a heating device. The inside 4 of the said casing forms a hearth for burning any solid or liquid fuel. The double-wall casing 3 possesses at its base a cold water supply tap 5 and an emptying 90 plug 6 and, at its upper part, it has a pipe 7 abutting upon the top of the fixed jacket 1. An auxiliary tap 8 enables water heated by the radiations of the hearth to be collected.

Inside the jacket 1 is the washing drum 9 95 which is made of perforated metal as usual. In accordance with the present invention this drum 9 does not dip into the liquid contained in the jacket 1, but it is provided at its periphery with two sets of sprinkling devices or 100

buckets 10 and 10^a each having a symmetrical form in relation to its own axis in such wise as to fulfill its functions in both directions in which the drum rotates. These buckets 10 and 10^a are formed by plain solid plates held in place by means of stays 11 between the cheeks 12' and 13' of the drum. The set of buckets 10 which are intended to deliver washing liquid onto the linen, have extensions 10^b running radially towards the center line of the drum, said extensions penetrating into corresponding deep longitudinal grooves 9^a of the washing drum. The other set of buckets 10^a placed between buckets 10 have no radial extensions and to said buckets 10^a correspond shallow longitudinal grooves 9^b of the washing drum. The function of these buckets of different shape will be explained later on. The drum 9, like the stationary jacket 1, is open at the end and presents on the same side as the opening 2 a central aperture 12, and it is mounted on the end of a shaft fitting into the hub 13 provided in the centre of the closed side. A reciprocating rotary motion can be given to the washing drum by any suitable mechanism, but a preferred form is that hereafter described which is specially adapted to the present machine.

On one side of the jacket 1 there is fastened a bracket 14 upon which there is mounted a pulley block as well as an automatic device for reversing the direction of rotation of the washing drum. This mechanism may be of any known type; Figure 5 represents a special arrangement which is particularly adaptable to the present machine. The machine is driven by a motor 15 (Figure 4) connected by belting, silent chain or the like to the pulley 16 of the pulley block. On both sides of the pulley 16 there are two smaller pulleys 17 and 18 one of which drives by means of straight-beling and the other by crossed belting two pulleys 19 and 20 mounted loosely upon the shaft 21 of the drum, and which thus rotate in opposite directions. These two pulleys are each laterally provided with a clutching surface 22 and 23, against which there alternately bear the corresponding surfaces 22' and 23' of a convex central pulley 24 keyed to the shaft 21, but adapted nevertheless to slide along said shaft. The shaft 21 is hollow and contains a sliding rod 25 traversed diametrically by the key 26. This later passes through a groove 27 made in the shaft 21 and having a length slightly greater than the distance of travel given to the key.

The mechanism for producing the alternating sliding movements of the rod 25 and consequently the lateral displacements of the central pulley 24, is composed as follows:

The sliding rod 25 is connected by means of a sleeve 28 and cross head 29 to a counterweight lever 30 having its fulcrum at 31. The shaft 21 of the washing drum, in its turn,

is provided with a worm 32 engaging a tooth sector 33 also having its pivotal point at 31 and extending beyond this point by means of an arm 34 which moves within a recess in the counterweight lever 30, limited by lateral stops 35 and 36, so as to cause oscillation of the counterweight as will be hereinafter described.

For operation of the machine there is introduced into the jacket 1 water up to the level X—X (Figure 1) situated a little lower than the lower part of the washing drum 9, which must not dip into the water. This level will not be exceeded owing to the presence of an overflow pipe 37 (Figure 2). The heater 3 is also filled with water which is heated by the radiations from the hearth 4. The linen is introduced at the end through the openings 2 and 12 in the washing drum and its jacket. When the washing drum rotates the buckets 10 will take liquid from the lower part of the jacket 1, raising it and pouring it through the perforations in the drum upon the linen which it contains, and which is thus moistened by sprinkling and not by seething, bubbling or effervescent action. The turned linen falls upon the bottom of the drum, but as this bottom does not contain water, the friction of the linen upon itself is not deadened or decreased as is the case in the ordinary ebullition or seething machines. Owing to the radial extensions 10^b of the buckets 10 the washing liquid is delivered practically up to the center of the drum, producing a very good aspersion of the linen. Since the other set of buckets 10^a have relatively short radial extensions the water taken from the jacket 1 is allowed to enter the drum before the buckets have reached the level of the center line of the drum. Thus the water runs along the inner wall of the drum, cleaning it off from all the impurities which accumulate thereon.

During the rotation of the drum 9 on its shaft 21, the tooth sector 33 travels over the worm 32, producing an angular displacement of the arm 34. When this arm encounters one of the lateral stops 35 or 36 of the counterweight lever 30 it induces an oscillation of the latter around its pivot 31 the result of which is a longitudinal sliding movement of the sliding rod 25 and consequently of the key 26 and the central pulley 24. If, prior to this sliding movement, the surfaces 22—22' for example should be in contact, then the surfaces 23, 23' would be those which come into contact after the movement, and the shaft 21 is then rotated in the same direction as the pulley 20, inversely to that of the pulley 19. Upon this reversal the movement of the toothed sector 33 and of its arm 34 is also reversed and the cycle of operations begins afresh, but in opposite direction. The length of the toothed portion of the sector is calculated so that the successive changes

in the rotation of the drum are effected after a predetermined number of revolutions.

Where it may be necessary to partially or fully renew the amount of water contained in the jacket 1, the water already heated will be taken from the heater 3, there being imparted to the water by any means the pressure necessary to conduct it through the pipe 7 up to the top of the jacket 1.

10 The advantages of the improved machine are as follows:

Better efficiency of the machine, by suppression of the bubbling or seething effect; silent running due to the absence of all noisy moving parts in the shafting; suppression of all auxiliary means for braking and stopping the washing drum at the moment when the direction of rotation is changed, as the braking is produced by the buckets which plunge 20 into the liquid in the tank 1; more constant effort demanded from the motor as the driving pulleys 19 and 20 always rotate in the same direction; finally reduction of machine floor space to a minimum, as the water heater 25 3 forms an integral part of the housing of the machine. This machine being of simple construction, is easy to attend to and to maintain and it can be constructed of small sizes and it is particularly well adapted to domestic 30 use.

What I claim is:

A washing machine comprising a stationary cylindrical jacket provided with a central opening at one end, a rotating unit with 35 in said jacket comprising a circular cheek provided with a central aperture, facing said central opening in the jacket, a second circular cheek coaxial with and spaced from said first circular cheek, a rotating shaft connected with said second cheek, a perforated cylindrical member coaxially mounted between said cheeks and provided with alternately arranged shallow and deep longitudinally extending perforated grooves, a plurality of 40 radially symmetrical buckets peripherally mounted between said cheeks adjacent to said grooves, radial extensions integral with said buckets extending into said deep longitudinal grooves and a plurality of stays passing 45 through said buckets and cheeks.

50 In testimony whereof I affix my signature.

PIERRE DIEBOLD.
